UNITED STATES PATENT OFFICE.

HERBERT J. LA JOIE, OF ORANGE, NEW JERSEY, ASSIGNOR TO AUTOPIANO COMPANY,
A CORPORATION OF NEW YORK.

PANEL AND PEDAL MECHANISM FOR MUSICAL INSTRUMENTS.

1,261,137.

Specification of Letters Patent.

Patented Apr. 2, 1918.

Application filed November 10, 1914. Serial No. 871,394.

To all whom it may concern:

Be it known that I, HERBERT J. LA JOIE, a citizen of the United States, residing at Orange, in the county of Essex and State of New Jersey, have invented a new and useful Panel and Pedal Mechanism for Musical Instruments, of which the following is a specification.

One form of automatic musical instrument is operated from pedals which are housed in the casing behind a vertically movable panel or door when the instrument is not to be used. When the instrument is to be used, the panel or door is raised to open the aperture and then the pedals are swung out to operative position. When the instrument is to be closed, the pedals are moved into the casing and the door lowered to close the aperture.

It is the object of the present invention to provide mechanisms whereby the panel can be raised to uncover the opening in the casing, and the pedals moved out to operative position at one operation; or the pedals moved back into the casing of the instrument and the panel lowered to close the aperture at another operation, and also to arrange the mechanism so that these operations can be performed from one handle or lever.

The best form of apparatus for practising the invention now known to me is shown in the accompanying drawing, in which,

Figure 1 is a front view of an instrument with the pedals housed inside of the casing and the panel lowered to close the aperture;

Fig. 2 is a view with the panel raised to open the aperture and the pedals moved out to operative position;

Fig. 2^a is a detail view of the operating handle;

Fig. 3 is an enlarged cross-sectional elevation showing the relative arrangement of panel and pedals when the latter are housed in the casing;

Fig. 4 is a similar view illustrating the position of parts when the pedals are in operative position;

Fig. 5 is a front elevation of part of the operating mechanism in the position occupied when the instrument is closed;

Fig. 6 is a view similar to Fig. 5, but show-

ing the parts in the position occupied after the door has been opened; and

Fig. 7 is also a view similar to Fig. 5, but showing the parts in the position occupied when the instrument is ready for operation.

Referring to the drawing and in detail, A designates the casing of an instrument which has a suitable aperture or opening in the front thereof, which opening can be closed by a panel or door B fitted to slide vertically in suitable ways on the inside of the casing.

P—P designate the pedals. The pedals are pivoted to a bar 10, which is connected by links 11, to a shaft 12 journaled in suitable blocks inside of the casing, the links being bent as shown. The pedals, bar and links can be turned up inside of the casing, as shown in Fig. 3, or the pedals can be moved out to operative position outside of the casing, as shown in Fig. 4, by rotating the shaft 12. Each pedal is connected by a link 13, to an arm 14, secured to the movable leaf of the suction bellows or feeder, the pivots between the links 13 and the arms 14 forming the turning points to guide the parts as the pedals are swung into or out of the casing.

A pinion 15 is secured on the shaft 12, and engaging this pinion is a sector 16, which has an extending arm 17, which is connected by a link 18 to a crank-arm 19 formed on the end of a shaft 20, journaled in suitable bearings carried by the casing and on the front end of which is arranged a crank-arm 21 having a pin or roller 22, which is operated, as hereinafter described. By turning the crank-arm 21 one way or the other, the pedals will be swung into or out of the casing.

A shaft 23 is journaled in a block or bearing secured to the casing and has an operating handle 24 formed or attached to its outer end, and a crank-arm 25 formed or secured to its inner end. A link 26 is connected to the arm 25 and to a bar 27, which is fitted to slide horizontally in a bearing on the inside of the casing.

Secured to, and below, the left-hand end of the bar 27, as shown in Figs. 1 and 2, is a plate or bar 28 which has a downwardly extending cam-shaped portion 29, engaging

which is a leaf-spring 30, which tends to push the same and the left-hand end of the sliding bar 27 upwardly. The plate 28 has a notch 31, which engages a pin 32 secured to the short arm of a pivoted bell-crank lever 33, the longer arm of which is connected by a link 34 to the sliding door or panel B.

The short arm of the bell-crank lever 33 has an extension 36, secured to which, and to the casing, is a spring 37 which, by pulling on said extension, tends to counterbalance the weight of the sliding panel or door B.

15 The sliding bar 27 has a plate 38 secured to, and above, the same, the left-hand part 39 of said plate being inclined or cam-shaped, as shown, and set in position to co-operate with a stud or roller 40 secured to 20 the frame-work. The plate 38 has a notch 41 set in position to engage the crank-pin or roller 22.

The operation of these parts is as follows: When the panel or door is lowered to 25 close the aperture in the casing, and the pedals are swung up into the instrument, the parts occupy the position shown in Figs. 1, 3 and 5.

When it is desired to play the instrument, 30 the operator takes hold of the handle 24 and swings the same, as indicated by the arrow in Fig. 1. This will move the sliding bar 27 to the left, and as the notch on the plate 28 engages the pin 32 during this 35 operation, the bell-crank lever 33 will be rocked and the sliding door or panel will be raised to open the aperture in the casing. This will bring the operating parts to the 40 position shown in Fig. 6. Just about the time this movement is completed, the incline 39 of the plate 38 will strike the stud 40 and the notch 41 of the plate 38 will engage the pin or roller 22 on the crank-arm 21. The continued rotation of the handle 24 will 45 continue to push the sliding bar 27 to the left, but as the incline or cam 39 works on the stud or roller 40, the left-hand end of the sliding bar 27 will have a downward movement, additionally, imparted thereto. 50 This will move the notch 31 clear of the pin 32 and will keep the notch 41 in engagement with the stud 22, so that this continued movement of the sliding bar to the left will operate the connections which control the 55 pedals, and will move the pedals out into operative position, the operating connections then assuming the position shown in Fig. 7.

Thus, by turning the handle 24, the panel 60 or door is first raised to open the aperture, and then the pedals are swung out into operative position.

A reverse movement of the handle will move the operating parts from the position 65 shown in Fig. 7 to the position shown in

Fig. 6, which will swing the pedals up into the casing and then will move the parts from the position shown in Fig. 6 to the position shown in Fig. 5, which will lower the panel or door to close the aperture in 70 the casing.

Thus, the reverse movement of the handle 24 will first swing the pedals up into the casing of the instrument and will then lower the panel or door to close the aperture. 75

By the operations thus described, all that the operator has to do is to throw the operating handle 24 from the position shown in Fig. 1 to the position shown in Fig. 2, when 80 it is desired to open the instrument for playing; or from the position shown in Fig. 2 to the position shown in Fig. 1, when it is desired to close up the instrument.

Many other connections may be devised 85 for carrying out the scope of my invention as expressed in the claims.

Having thus fully described my invention, what I claim and desire to secure by Letters-Patent is:—

90

1. The combination of a musical instrument having a casing, a pedal opening in said casing, a vertically movable panel for said opening, operating pedals in said casing arranged for movement through said opening to operative position outside the casing, an operating handle, a bar slidable by said handle, a member connected to move said panel, a second member connected to move said pedals, and means effective to cause said bar to operatively engage said members successively in timed relation, said means comprising a cam plate on said bar, a fixed stud, and a spring effective to maintain said cam plate in yielding engagement with said stud during the operative movement of said bar.

95

2. The combination of a musical instrument having a casing, an opening in said casing, a vertically movable panel, operating 110 pedals in said casing and arranged so that they can move to operative position outside the casing, an operating handle, and connections from said operating handle, comprising a sliding bar having a plate with a 115 notch, a crank-pin for said notch to engage, said crank-pin being connected to the pedals, said bar having another plate having a notch, a crank-pin which said notch can engage, and connections from said crank-pin 120 to raise or lower the panel.

105

3. The combination of a musical instrument having a casing, an opening in said casing, a vertically movable panel, operating 125 pedals in said casing and arranged so that they can move to operative position outside of the casing, an operating handle, and connections from said operating handle, comprising a sliding bar carrying a plate having a notch, a crank-pin which said notch 130

engages connected to the panel, said bar having another notched plate, a crank-pin which said notch engages, connections therefrom to the operating pedals, the end of said notched plate being formed into a cam, and a pin on the casing which said cam engages. 5

4. The combination of a musical instrument having a casing, an opening in said casing, a vertically movable panel, operating pedals in said casing and arranged so that they can move to operative position outside the casing, an operating handle, and connections from said operating handle comprising a sliding bar, a notched plate 10 secured thereto below the same, a crank-pin with which said notch engages connected to the panel, a notched plate secured to the sliding bar above the same, a crank-pin with which said notch engages, and connections 15 therefrom to the operating pedals.

5. The combination of a musical instrument having a casing, a pedal opening in 20

said casing, a vertically movable panel for said opening, operating pedals in said casing arranged for movement through said opening to operative position outside the casing, an operating handle, a bar slideable by said handle, a member connected to move said panel, a second member connected to move said pedals, and means on said sliding bar 25 effective to cause said bar to operatively engage said members successively in timed relation, said means comprising a cam plate on said bar engaging a fixed stud and thereby moving said bar to successively engage 30 said members.

In testimony whereof I have hereunto set my hand, in the presence of two subscribing witnesses.
